UNITED STATES PATENT OFFICE.

JOHN G. KING, OF MORRISTOWN, NEW JERSEY.

PASSENGER-IDENTIFICATION DEVICE.

Application filed May 22, 1923. Serial No. 640,695.

To all whom it may concern:

Be it known that I, JOHN G. KING, a citizen of the United States, and a resident of Morristown, county of Morris, and 5 State of New Jersey, have invented certain new and useful Improvements in Passenger-Identification Devices, of which the following is a specification.

This invention relates to an improved device for identifying passengers in a conveyance, such as a railway car, and is adapted to be used by the conductor when he takes up the tickets, by marking on a destination insignia of a ticket so that the passenger need not be repeatedly requested to show his ticket.

The invention relates further to a means for carrying the ticket so that it relates to respective passengers in a seat, the usual 20 two-passenger seat of a car having a ticket with right and left divisions to identify these right and left passengers.

The invention is illustrated in the accompanying drawing, in which Figure 1 is a 25 perspective view of the back of a car seat with the device in place. Figure 2 is a detail face view of a ticket illustrating my invention, and Figure 3 is a side view thereof with one end of the ticket in section. 30 Figure 4 is a view of a modified form of stud. Figures 5 and 6 are a face and side view, respectively, of a modified form of holder with a ticket thereon.

In the drawing I show the device as applied to a railway car seat for two passengers, and the ticket is secured to the upper edge of the back 10 of the seat and refers to the passengers in the seat next in rear. This disposition can be changed to meet 40 conditions.

The ticket 11 is held so that it can be written on, the conductor when he takes up the passenger's ticket marking on the face of the ticket the passenger's destination.

45 The destination insignia is printed on the face of the ticket and can be in the form of numerals designating stations in the train's run. The ticket illustrated in the

drawing refers to two passengers, and I show the ticket as filled out for one, the 50 passenger in the left hand side of the seat.

Assuming the train starting at New York, if the passenger's ticket carries him to Philadelphia and the seventh station is Philadelphia, the conductor marks the "7" 55 of the numeral insignia in any prescribed way, for instance, by initialing as at 12.

The tickets 11 are placed in the device before the train leaves, or they can be inserted by the conductor, the former being 60 preferred as it saves time in collecting. The ticket is held so that it can be written on easily, being reenforced and firmly held, in one instance, as in Figures 1, 2 and 3, by the upper edge of the back of the seat itself. The ticket is readily attached and detached, and for this purpose I may use studs 13 which are driven or screwed into the back 10 and project slightly above the 65 upper surface thereof so that the ends of 70 the ticket can be slipped under the heads 14.

The tickets have slots 15 to receive the studs 13 to prevent lateral movement of the tickets. A modified form of stud is shown in Figure 4, in which the head 16 is 75 recessed at 17 to receive the slot 15 of a ticket.

The ticket may have the dividing line 18 or an equivalent mark to separate the insignia markings. When the passenger identified by the initialing 12 leaves the train and another passenger occupies it, getting on at the station indicated by 7, say Philadelphia, and the second passenger has a ticket to Baltimore, indicated by 14, for instance, then the conductor marks 14 with his initials or other mark 19. The ticket shown in Figure 2 indicates that the right hand side of the seat was unoccupied.

In case the upper part of the seat of the 90 car is too soft to provide a solid backing to permit comfortable writing on the ticket, I may provide a plate 20 which is adapted to be secured by suitable means, such as the screws 21, to the back of the 95 seat, the ticket 11 being placed on the plate

20 and having the slotted ends slipped under the heads 22 of the studs 23 on the plate 20.

I claim:

- 5 1. A passenger identification device comprising a plate, a ticket with slotted ends, and headed studs securing the plate to a support and also adapted to receive said slotted ends and hold the ticket flat on the plate.
- 10 2. In a device of the kind described com-

prising a backing plate, a ticket with slots in opposite edges, and headed studs to hold the plate permanently on a support and to hold the ticket removably in place at the slots.

In testimony that I claim the foregoing, I have hereto set my hand, this 18th day of May, 1923.

15

JOHN G. KING.
